MACHINE AND PROCESS FOR MAKING HAIR
WAVING PADSCurt J. Rohland, Seekonk, Mass., assignor to The
Nestle-Le Mur Company, a corporation of Ohio

Application August 4, 1933, Serial No. 683,613

33 Claims. (Cl. 112—2)

This invention relates to a machine for assembling sheet material and has for one of its objects a mechanical formation and assembling of several plies of material and attaching the same together to provide an article such as a pad used for permanent hair waving.

Another object of the invention is the utilizing of one web of paper for forming a plurality of the plies of material to be assembled by folding the web of paper.

Another object of the invention is the provision of a device for mechanically assembling sheets of material by feeding the material continuously without interruption through the machine in order that the production of the machine may be increased.

Another object of the invention is to continuously feed one of the webs of material through the machine and intermittently feed other webs of material into the desired relation with this web, and to cut off these other webs without interruption of the feed.

Another object of the invention is the proper positioning of the different plies of material prior to their attachment together.

Another object of the invention is the provision of a sewing attachment which will sew the plies of material into assembled relation while in continuous passage through the machine.

A further object of the invention is the printing of the finished assembly while continuously passing through the machine and without stopping the same.

With these and other objects in view, the invention consists of certain novel features of construction, as will be more fully described, and particularly pointed out in the appended claims.

In the accompanying drawings:

Fig. 1 is a plan view of the machine with the supports for the supply webs of material omitted.

Fig. 2 is a side elevation with the supports for the material omitted.

Fig. 3 is a section substantially on the line 3—3 of Fig. 1, showing the parts adjacent the line of section.

Fig. 4 is a section on substantially line 4—4 of Fig. 3, illustrating the transmission of power by gearing to the main feed rolls.

Fig. 5 is a section on substantially line 5—5 of Fig. 4.

Fig. 6 is an end view or section on substantially the line 6—6 of Fig. 5 showing work as positioned between the rolls.

Fig. 7 is a fragmental detail view substantially on line 7—7 of Fig. 1.

Fig. 8 is a schematic view illustrating the feed and assembly of the material through the machine.

Fig. 9 is a perspective view looking at the folding device for the main web of material from the opposite side of Fig. 8 from that upon which the view Fig. 9 is located.

Fig. 10 is a section on the line 10—10 of Fig. 8.

Fig. 11 is a section on the line 11—11 of Fig. 8.

Fig. 12 is a section on the line 12—12 of Fig. 9.

Fig. 13 is a perspective view illustrating the inserting of flannel between the main web of material and a portion of the stitching of a previously inserted piece of flannel.

Fig. 14 is a schematic view of the arrangement 15 of the feed rolls for certain parts of the machine.

Fig. 15 is a top plan view of the finished article.

Fig. 16 is a sectional view therethrough.

Fig. 17 is an elevation of the needle mounting and the looper below.

Fig. 18 is an elevational view showing another 20 position of the structure shown in Fig. 17.

Referring to the drawings, this machine may be used for the assembly of various materials and for illustrative purposes I am showing a permanent hair waving pad as one illustration of an article which this machine can produce.

This pad as illustrated in Figs. 15 and 16 shows a ply of tinfoil 20 with a web of paper folded as at 21 to provide a ply 22 and a ply 23 of paper 30 on either side thereof. There is inserted between these plies 22 and 23 at their free edges a ply of material 24 of flannel and the entire assembly is stitched together by a line of stitching 25 as will be clearly indicated in these views Figs. 15 35 and 16.

In order that the general scheme of procedure may be understood before the details of the machine are described, I will refer to Fig. 8 which illustrates a reel 26 of a web of paper 27 which is 40 drawn from the reel by feed rolls 28 and 29 through a folding device 30 which is assisted by a double taper roller 31 which also guides the paper at the start of its folding movement. As this web of paper is continuously fed by rolls 28 45 and 29 a web of tinfoil 32 is drawn from the reel 33 intermittently by roll 34 and its companion roll 35 and inserted between the folded web of paper after which it is severed by a cutter 36 and pinched and fed forward by the companion 50 rolls 37 above and 38 beneath which intermittently grip and feed it forward. A web of flannel 39 is fed intermittently from a reel 40 by rolls 41 above and 42 beneath to position the end of the flannel just inside of the free edges of the folded 55

paper after which the flannel is cut off by a cutter knife 43 and then the flannel is gripped and fed forwardly by the intermittently acting feed rolls 44 above and 45 beneath to position the work under the needle 46, which performs the sewing operation, while the parts are travelling through the machine, being drawn continuously through all of the operations by the cylindrical feed rolls 28 and 29.

10 At certain intervals, between the portions of tinfoil and felt inserted, the cutter knife 47 will operate to cut the web of material or paper after which it will be picked up by the roll of the printing press 48 and fed out of the machine at which time the printing will take place.

15 The operation of the mechanism which I have described will be more fully hereinafter explained. The bed of the machine, designated 50, see Fig. 2, is supported from the floor by a suitable framework 51 having legs 52. There is bolted onto this framework 51 an angle iron 53 which extends several feet beyond the bed of the machine and is provided with a spindle 54 to suitably support the roll 28 of the main web of paper. An angle iron 55 is also supported by the framework and bed of the machine to extend at right angles to the angle iron 53 and provides a suitable support for shaft 56 upon which the rolls 33 and 48 for the tinfoil and flannel are mounted.

20 25 30 35 40 45 An electric motor 57, see Fig. 3, is mounted on a platform 58 supported from the bed 50 of the machine by hangers 59. This motor drives a pulley 60 through a friction clutch 61 operated by a bell crank lever 62 having an arm 63 and handle 64 urged in one direction by a spring 65 to disconnect the clutch from this pulley 60. Power is transmitted by the belt 66 to the pulley 67 on the shaft 68 of the machine, which directly drives the sewing mechanism of my machine. From this shaft 68 power is transmitted to the main shaft 69 of my machine by suitable gearing housed within the compartment 70. At one end of the shaft 69 there is provided a spiral gear 71 meshing with spiral gear 72 to transmit power to the cross shaft 73 of the machine which extends at right angles to the main shaft 69.

50 55 60 65 The main feed roll 28, see Figs. 1 and 4, is driven from the cross shaft 73 through a train of gears 74, 77, 78, and 79, shaft 75, and train of gears 78, 80 and 81, the latter being mounted upon the shaft 82 upon which roll 28 is mounted. This gear 81 also drives the shaft 83 for the lower roll 29 by means of the gear 84 mounted on this shaft and meshing with gear 81.

60 65 70 75 The upper roll 28 and its gear are mounted in a bracket 85 which tends to be moved upwardly out of mesh with the gearing by a spring 86 and is moved downwardly by a screw 87 operated by a knurled finger piece 88 acting through a suitable arm 89 on the framework 90 for the gearing shown.

65 70 75 80 85 90 95 Above the cross shaft 73 there is mounted a short shaft 91, see Figs. 2 and 3, which is driven from the cross shaft 73 through gear 92 mounted on the cross shaft 73 and gear 93 mounted on the shaft 91. Upon this shaft 91, there is mounted a spiral gear 94 for driving the upper feed roll 34 which moves the tinfoil into position, the lower roll 35 being a cylindrical rubber roll and not driven. The rolls 34 are suitably supported on shafts 96 and 97 mounted in suitable bearings. There is also a similar feed mechanism for the flannel consisting of a spiral gear 98 on the shaft 91 which drives a spiral gear 99 on shaft 100 for driving the feed roll 41 while the lower

5 roll 42 is cylindrical and of resilient material such as rubber. This shaft 100, and the similar shaft 101 for the cylindrical roll are suitably supported in bearings provided above the bed of the machine.

5 10 15 20 25 30 35 40 45 50 55 60 65 70 75 80 85 90 95 100 A cutter 36 for the tinfoil, see Figs. 1 and 2, is mounted upon an arm 102 which is secured to the shaft 103 mounted in bearing 104 for rotation about its axis by arm 105 locked thereto by a pin. This cutter is moved towards the fixed cutting edge with which it cooperates by spring 106. There is also similarly arranged for the flannel web a cutter 43 which is mounted on arm 107 secured to shaft 108 extending through bearing 109 and having an arm 110 locked thereto by a pin. This cutter 43 is moved towards its fixed cooperating edge by a spring 111. Each of these arms 105 and 110 is provided with extensions 112 and 113 to be respectively engaged by cams 114 and 115 mounted on cross shaft 73 for swinging these arms to operate the cutters 36 and 43. These arms are raised to raise the cutters by springs 116 and 117 which act to maintain the lateral portions 112 and 113 in the path of movement of these cams.

5 10 15 20 25 30 35 40 45 50 55 60 65 70 75 80 85 90 95 100 105 110 115 120 125 130 135 140 145 150 The upper feeding roll 37, see Figs. 4 and 5, is mounted upon shaft 120 upon which is also mounted gear 121 which meshes with gear 122 on the shaft 123, which shaft carries the lower roll 38. This gear 122 is driven from shaft 13 30 by gear 14 and the intermediate gear 124.

5 10 15 20 25 30 35 40 45 50 55 60 65 70 75 80 85 90 95 100 105 110 115 120 125 130 135 140 145 150 155 A folder for guiding the web of material 27 is mounted upon an extension arm 125, see Fig. 9, suitably secured to the bed of the machine or the framework thereof. This extension arm 125 supports post 126 which carries an arm 127 for suitably supporting the folder 30. This folder consists preferably of a sheet of metal 128 doubled upon itself as at 129 in substantially a U-form with flaring edges 130 while the inside 40 of the folder consists of another strip of sheet metal 131 doubled upon itself as at 132 with flaring edges 133 bent over and secured to the flaring edges 130 as at 134, the arrangement being such as to leave a space 135 or U-shaped 45 passage between these inner and outer parts. The inner part designated generally 131 is of greater extent than the outer part 128 as will be illustrated by the dotted lines in Fig. 8, the extent being such that the end 136 of this inner 50 part will be adjacent the cutter 36 which severs the tinfoil so that as the paper 27 is fed through the folder and emerges therefrom, the edges will be spaced apart by reason of the guide 135 and the upper edge will engage the cutter 36, as illustrated at 137, in Fig. 12, to hold this upper part outwardly so that the web of tinfoil 32 will be assured of entry between the folded plies of the web 27, such as illustrated in Fig. 12.

5 10 15 20 25 30 35 40 45 50 55 60 65 70 75 80 85 90 95 100 105 110 115 120 125 130 135 140 145 150 155 160 This web of tinfoil is fed forwardly by the rolls 34 and 35 which are rubber rolls shaped as illustrated in Fig. 14. The feeding surface 140 of the upper roll is of a length which it is desired that the tinfoil shall be fed forwardly and the remainder of the surface 141 is cut 65 away, while the lower roll is cylindrical as shown. The upper roll rotates continuously while the lower roll only rotates when the tinfoil is gripped intermittently and fed forwardly a distance equal to the surface 140 of these 70 rolls. The tinfoil is drawn from its reel 33 and fed in and out about the tension bars 142 and 143 and beneath the cutter 36, and the tinfoil is fed into the open edge of the web of paper 27, as illustrated in Fig. 12, while this paper is 75

in motion. As soon as the feed of the tinfoil is completed the cutter quickly acts longitudinally of the travel of the web of paper 27 to cut off this foil as it is travelling with the web 5 27. As the foil reaches the inside fold of the web 27, it is gripped by the auxiliary feed rolls 31 and 38 which are shaped as illustrated in Figs. 5 and 6 with both of their engaging surfaces such as 140 so arranged as to grip the 10 fold with the tinfoil therein after it has completed its feed and will thus bind the tinfoil during the cutting action of the cutter 36 as well as assist it to be fed forwardly with the web of folded paper 27.

15 As the web of folded paper 27 with the tinfoil assembled therein approaches the line of feed of the flannel web 39, the paper web is spread apart by a guide member 145, illustrated most clearly in Fig. 13. This guide member 145 is 20 a strip of sheet material having a bottom layer 146 bent as at 147 to provide doubled over portions 148 having upwardly turned projections 149. This guide is positioned between two plies of the material 27 and so located as to be above 25 the tinfoil which has been inserted in position. The guide member will open the two folds of the doubled paper 27 for the reception of the flannel 39 which is to be inserted therein.

This flannel is drawn from its reel 40 over 30 tension bars 150 by the rolls 41 and 42 which are shaped similarly to the diagrammatic layout in Fig. 14, providing an engaging surface 140 to feed the felt the desired amount forwardly so that its end enters beneath the marginal edges 35 of the folded strip of web 27 and is limited in its movement in this direction by the fold 147 of the guide member 145. As soon as this forward movement of the felt or flannel is completed the cutter 43 descends to sever a piece of 40 felt which will be designated 151 from its web and at the time of severing and at the end of the forward feed of this flannel web the same is gripped by the continuously rotating altho intermittently gripping feed rolls 44 and 45 which 45 are shaped similarly to the layout in Fig. 6, to feed this flannel forwardly and beneath the needle 152 of the sewing machine, which needle is mounted in a reciprocating bar 153, it being understood that the rolls 44 and 45 feed the 50 flannel at substantially the same rate as the main web of folded paper is fed forwardly by the main feed rolls 28 and 29.

The sewing machine is driven directly from the shaft 68 upon which there is mounted an eccentric 155, which reciprocates the arms 156 and 157 of the bell crank lever pivoted at 158. The arm 157 is secured to the needle bar 153 by a screw 159 for actuating it. This needle bar 55 153 is guided through a bore 160 in the frame 161 of the sewing machine, which bore 160 is of a dimension larger than the needle bar 153. At the upper end of the needle bar a strap 162 is fixed thereto and embraces a standard 163 which 60 is offset at its upper end as at 164 so as to permit lateral movement of the spindle after the same is lowered from the position shown in Fig. 17. A lower guide consisting of a block 165 is supported in position by a strap 166 secured to the frame by rivets 167 which permits the block 165 to move towards and from the frame 161 and which is forced outwardly by a spring 168 located in a recess 169 in the frame. Thus as the needle bar 153 descends in a vertical path it enters the travelling web and is 65

70 moved by the travelling web forwardly so that the block 165 will compress the spring 168 and after the spindle withdraws the needle from the work this spring will force the block 168 back against the end of the strap 166 and the guide 75 162 will move the upper end of the needle bar so as to vertically align the same for the next downward stroke of the needle in passing through the work.

76 Looper 170 is of more or less standard construction and will engage the thread at the end 10 of the needle and cause it to form a loop which will be locked upon the next stroke of the needle as is usual in a single thread chain stitch arrangement of this character. 15

After a predetermined length of continuous sewing of the different plies of fabric has been accomplished, the work is severed by the cutter 47, which cooperates with the lower fixed jaw or edge 175 for completing the shearing action at the desired point. This cutter 47 is secured to an arm 176 mounted upon shaft 177 which has a lever 178 secured thereto and provided with a roller 179 extending laterally therefrom and setting in a recess 180 of the slide 181, which is suitably guided 20 between a pair of rolls 182 and is moved forwardly by a spring 183 to open or raise the cutter. This slide is provided with a slot 184 through which the shaft 69 extends and is also provided with a laterally-extending pin 185 to be engaged by a 25 cam 186 secured to a shaft 69 so that as this cam rotates it will move the slide rearwardly to swing the arm 178 and move the cutter downwardly to sever the work after which the spring 183 raises the cutter as above set forth. This action is accomplished very quickly with comparison to the feed of the web and such portion of the web as is fed during the passage of the cutter below the plane of the feed of the web accumulates by arcing upwardly in back of the cutter 47. The 30 amount of arcing is such that when the cutter rises again and the web is free to move forwardly it quickly straightens out in its path of travel 35 forwardly.

As the work is cut off by the cutter 47, it is 40 picked up by the printing press and discharged from the machine. This printing press, as illustrated more particularly in Figs. 1 and 2, consists of a mutilated cylinder or drum 190 mounted upon shaft 191, the extent of the engaging surface of this mutilated cylinder being the length 45 of the printing which will be imparted upon each piece of work. This cylinder feeds against a rubber roll 192 which is mounted upon shaft 193 so that as the work is printed it will have a support and will also be fed forwardly out of the machine and down the inclined discharge chute 50 55 194.

The printing roll and rubber support or platen roll 193 are driven from the main shaft 69 through 60 spiral gears 195 and 196, shaft 197, gear 198 on shaft 197 and gear 199 on shaft 193, which in turn drives gear 200 on shaft 191 and also drives gear 201 on shaft 202 which is provided with a 65 cam 203 mounted thereon.

In order that the mutilated printing roll 190 may be properly inked, I have provided an ink reservoir 204 which has a roll 205 to transfer the ink from this reservoir to roll 206 thence to roll 207, roll 208, roll 209 and to roll 210 which in turn 70 contacts with the printing surface of the drum 190. The roll 208 is driven from shaft 193 by a sprocket chain 211 engaging gear 213 on shaft 193 and engaging gear 212 on shaft 220 for roll 208, 75

which being in frictional contact with the other rolls causes their rotation.

Roll 208 is out of normal contact with the directly contacting inking roll 210 and is moved into engagement therewith by an arm 214 which is oscillated by a cam 203 so that each time the printing drum rotates the supports for the inking rolls will rock about shaft 220 to cause contact between the rolls 209 and 210 so that the ink will be supplied to the roll 210 and in turn be delivered to the printing roll or drum 190. Suitable adjustment may be provided for the deposit of ink onto the roll 206 by a thumb screw 215 opening the gate which controls the amount supplied. The 15 desired tension may be maintained on the sprocket chain by an arm 216 and an idler 217.

It is also desirable that a traverse motion be imparted to the inking mechanism and I mount cams 218 and 219 on shaft 220 which has the gear 212 mounted thereon. These cams engage the roller abutments 221 and 222 and cause a small traverse movement which is permitted by the length of the sprocket chain, for the better distribution of the ink.

25 Suitable counting mechanism may be provided to operate upon the rotation of the printing mechanism or some other part as each shaft turns one revolution for each pad formed.

The foregoing description is directed solely to 30 towards the construction illustrated, but I desire it to be understood that I reserve the privilege of resorting to all the mechanical changes to which the device is susceptible, the invention being defined and limited only by the terms of the appended claims.

It is apparent that the mechanism, as described, might also be utilized without the side feed of the absorbent material 39 or the foil material 32, as indicated in Figure 8 and it is also 40 apparent that the printing mechanism, as shown in Figures 1 and 2 might be omitted.

The present application is a continuation in part of application, Serial No. 678,162, filed June 29, 1933 and it is continued in part in application, 45 Serial No. 37,285, filed August 22, 1935, all of which applications are directed to sewing together of a plurality of sheets or webs of material in partly or wholly superimposed condition for making hair waving pads.

50 The present application is adapted for making hair waving pads both for spiral waving and for Croquignole waving.

I claim:

1. In a machine for making hair waving pads 55 of the type composed of a sheet or web of a nonpermeable wrapper material and an attached sheet or web of an absorbent material, said machine being provided with holders for continuous rollers of said wrapper and absorbent materials, 60 and runways for receiving said sheet or web materials when they are taken off said rollers and during assembly, sewing together, separating and imprinting of said hair waving pads; the combination with said machine of means for continuously feeding a web of material through the machine, means for intermittently feeding another web of material into assembled relation therewith, and a sewing machine for attaching the sheets of material together, said sewing machine being capable of sewing said sheet materials together 65 while said sheet materials are moving and being provided with means whereby the needle upon being inserted to form a stitch will move with the fabric and will be withdrawn after the fabric has moved a predetermined distance.

2. In a machine for assembling sheet material, means for continuously feeding a web of material through the machine, means for intermittently feeding a plurality of other webs of material into assembled relation therewith, each at a different point in the travel of the continuously fed web, and a sewing machine for attaching the webs of material together, said sewing machine being capable of sewing said sheet materials together while said sheet materials are moving and being provided with means whereby the needle upon being inserted to form a stitch will move with the fabric and will be withdrawn after the fabric has moved a predetermined distance.

3. In a machine for assembling sheet material, 15 means for continuously feeding a web of material through the machine, means for intermittently feeding another web of material at right angles to the feed of the first web into assembled relation therewith, means for severing the second said 20 web, and a sewing machine for attaching the sheets of material together, said sewing machine being capable of sewing said sheet materials together while said sheet materials are moving and being provided with means whereby the needle 25 upon being inserted to form a stitch will move with the fabric and will be withdrawn after the fabric has moved a predetermined distance.

4. In a machine for assembling sheet material, 30 means for continuously feeding a web of material through the machine, means for intermittently feeding a plurality of other webs of material at right angles to the feed of the first web and into assembled relation therewith, each at a different point in the travel of the continuously fed web, 35 means for severing said right angularly fed webs, and a sewing machine for attaching the webs of material together, said sewing machine being capable of sewing said sheet materials together while said sheet materials are moving and being 40 provided with means whereby the needle upon being inserted to form a stitch will move with the fabric and will be withdrawn after the fabric has moved a predetermined distance.

5. In a machine for assembling sheet material, 45 means for continuously feeding a web of material through the machine, means for folding said web of material, and means for intermittently feeding another web of material between the overlying plies of said folded web, said intermittent feeding 50 means feeding said web of material transversely to the movement of the folded web and means for cutting off said second-mentioned web of material when it has been fed in position between the folded web.

6. In a machine for assembling sheet material, 55 means for continuously feeding a web of material through the machine, means for folding said web of material, means for intermittently feeding a plurality of other webs of material between the overlying plies of said folded web at different points in the travel of said continuously fed web, and a sewing machine for attaching said sheets of material together, said sewing machine being capable of sewing said sheet materials together 60 while said sheet materials are moving and being provided with means whereby the needle upon being inserted to form a stitch will move with the fabric and will be withdrawn after the fabric has moved a predetermined distance.

7. In a machine for assembling sheet material, 70 means for continuously feeding a web of material through the machine, means for folding said web of material, means for causing the free edges of the folded web to gap open, means for intermit- 75

tently feeding another web of material between the overlying plies of said folded web, means for severing said inserted web, and a sewing machine for attaching said webs of material together, said 5 sewing machine being capable of sewing said sheet materials together while said sheet materials are moving and being provided with means whereby the needle upon being inserted to form a stitch will move with the fabric and will be 10 withdrawn after the fabric has moved a predetermined distance.

8. In a machine for assembling sheet material, means for continuously feeding a web of material through the machine, means for folding said web 15 of material, means for causing the free edges of the folded web to gap open, means for intermittently feeding a plurality of other webs of material between the overlying plies of said folded web at different points in the travel of said continuously fed web, means for severing said 20 inserted webs, and a sewing machine for attaching said sheets of material together, said sewing machine being capable of sewing said sheet materials together while said sheet materials are 25 moving and being provided with means whereby the needle upon being inserted to form a stitch will move with the fabric and will be withdrawn after the fabric has moved a predetermined distance.

30 9. In a machine for assembling sheet material, means for continuously feeding a web of material through the machine, means for folding said web of material, means for intermittently feeding another web of material between the overlying plies of said folded web, means for severing the material so inserted, means for feeding an additional web to position its end between the edges of said folded web, means for severing the last said web, and a sewing machine for attaching 35 said webs together, said sewing machine being capable of sewing said sheet materials together while said sheet materials are moving and being provided with means whereby the needle upon being inserted to form a stitch will move with the fabric and will be withdrawn after the fabric has moved a predetermined distance.

40 10. In a machine for assembling sheet material, means for continuously feeding a web of material through the machine, means for folding said web of material, means for intermittently feeding another web of material between the overlying plies of said folded web, means for severing the material so inserted, means for feeding an additional web to position its end between the edges of said folded web, means for severing the last said web and means for sewing the open edges of the folded web together with the two additional webs between the plies thereof, said last-mentioned means being capable of sewing the webs while moving and being provided with a needle which when inserted into said webs will move with said webs until withdrawn therefrom after the stitch is formed.

45 11. In a machine for making hair waving pads of the type composed of a sheet or web of a non-permeable wrapper material and an attached sheet or web of an absorbent material, said machine being provided with holders for continuous rollers of said wrapper and absorbent materials, and runways for receiving said sheet or web materials when they are taken off said rollers and during assembly, sewing together, separating and imprinting of said hair waving pads; the combination with said machine of means for continuously feeding a web of material through the machine, means for folding said web of material, means for intermittently feeding another web of material between the overlying plies of said folded web, and means for sewing the open edges of the folded web together while travelling forwardly through the machine, said last-mentioned means being capable of sewing the webs while moving and being provided with a needle which when inserted into said webs will move with said webs until withdrawn therefrom after the stitch is formed.

50 chine, means for folding said web of material, means for intermittently feeding another web of material into assembled relation therewith, a sewing machine for attaching the sheets of material together, and means for severing the first web between the inserted additional plies, said sewing machine being capable of sewing said sheet materials together while said sheet materials are moving and being provided with means whereby the needle upon being inserted to form a stitch will move with the fabric and will be withdrawn after the fabric has moved a predetermined distance.

55 12. In a machine for assembling sheet material, means for continuously feeding a web of material through the machine, means for folding said web of material, means for intermittently feeding another web of material between the overlying plies of said folded web, means for severing the material so inserted, means for feeding an additional web to position its end between the edges of said folded web, means for severing the last said web, means for sewing the open edges of the folded web together with the two additional webs between the sewed edges, and means for severing the folded web between the points of insertion of the additional webs.

60 13. In a machine for making hair waving pads of the type composed of a sheet or web of a non-permeable wrapper material and an attached sheet or web of an absorbent material, said machine being provided with holders for continuous rollers of said wrapper and absorbent materials, and runways for receiving said sheet or web materials when they are taken off said rollers and during assembly, sewing together, separating and imprinting of said hair waving pads; the combination with said machine of means for continuously feeding a web of material through the machine, means for intermittently feeding another web of material into assembled relation therewith and means for sewing the webs of material together while continuously travelling through the machine, said last-mentioned means being capable of sewing the webs while moving and being provided with a needle which when inserted into said webs will move with said webs until withdrawn therefrom after the stitch is formed.

65 14. In a machine for making hair waving pads of the type which will assemble together a plurality of webs of materials including a sheet of an absorbent fabric, a sheet of paper and a sheet of a metal foil by sewing them together along one of their respective edges, said machine being provided with holders for continuous rolls of said absorbent fabric material, said paper material and said metal foil material, and runways for receiving said sheet materials when they are taken off said rollers and during assembly, sewing together, separation and imprinting of said hair waving pads; the combination with said machine of means for continuously feeding a web of material through the machine, means for folding said web of material, means for intermittently feeding another web of material between the overlying plies of said folded web, and means for sewing the open edges of the folded web together while travelling forwardly through the machine, said last-mentioned means being capable of sewing the webs while moving and being provided with a needle which when inserted into said webs will move with said webs until withdrawn therefrom after the stitch is formed.

70 15. In a machine for making hair waving pads of the type composed of a sheet or web of a

nonpermeable wrapper material and an attached sheet or web of an absorbent material, said machine being provided with holders for continuous rollers of said wrapper and absorbent materials, 5 and runways for receiving said sheet or web materials when they are taken off said rollers and during assembly, sewing together, separating and imprinting of said hair waving pads; the combination with said machine of a pair of rolls for continuously feeding a web of material through the machine, another pair of rolls for intermittently feeding another web of material into assembled relation with the continuously traveling web and at an angle thereto, one of said last 10 mentioned rolls being a mutilated roll with a portion of its surface cut away and leaving the working surface equal to the length of feed of the material, and means for attaching the sheets of material together, said last-mentioned means including a sewing machine for continuously stitching said webs of material together while they are moving, said means being provided with a stitching needle moving with the webs of material while forming a loop.

16. In a machine for making hair waving pads of the type which will assemble together a plurality of webs of materials including a sheet of an absorbent fabric, a sheet of paper and a sheet of a metal foil by sewing them together along one of their respective edges, said machine being provided with holders for continuous rolls of said absorbent fabric material, said paper material and said metal foil material, and runways for receiving said sheet materials when they are taken off said rollers and during assembly, sewing together, separation and imprinting of said hair waving pads; the combination with said machine of a pair of rolls for continuously feeding a web of material through the machine, another pair of rolls for intermittently feeding another web of material into assembled relation with the continuously traveling web and at right angles thereto, one of said last mentioned rolls being a mutilated roll with a portion of its surface cut away and leaving the working surface equal to the length of feed of the material, and means for attaching the sheets of material together, said last-mentioned means including a sewing machine for continuously stitching said webs of material together while they are moving, said means being provided with a stitching needle moving with the webs of material while forming a loop.

17. In a machine for making hair waving pads of the type which will assemble together a plurality of webs of materials including a sheet of an absorbent fabric, a sheet of paper and a sheet of a metal foil by sewing them together along one of their respective edges, said machine being provided with holders for continuous rolls of said absorbent fabric material, said paper material and said metal foil material, and runways for receiving said sheet materials when they are taken off said rollers and during assembly, sewing together, separation and imprinting of said hair waving pads; the combination with said machine of a pair of rolls for continuously feeding a web of material through the machine, a plurality of spaced pairs of rolls intermittently feeding a plurality of spaced webs of material into assembled relation with the continuously traveling web at spaced points thereon and at right angles thereto, one of each of the last mentioned rolls being a mutilated roll with a portion of its surface cut away and leaving the working surface equal to the length of feed of the material, and means for attaching the sheets of material together, said last-mentioned means including a sewing machine for continuously stitching said webs of material together while they are moving, said means being provided with a stitching needle moving with the webs of material while forming a loop.

18. In a machine for assembling sheet material, a pair of rolls for continuously feeding a web of material through the machine, a plurality of spaced pairs of rolls intermittently feeding a plurality of spaced webs of material into assembled relation with the continuously traveling web at spaced points thereon and at right angles thereto, one of each of the last mentioned rolls being a mutilated roll with a portion of its surface cut away and leaving the working surface equal to the length of feed of the material, means for severing a portion from each of said intermittently fed webs, and means for attaching the severed sheets of material together and to the continuously traveling web.

19. In a machine for assembling sheet material, a folding device, a pair of rolls for continuously feeding a web of material through said folding device, a plurality of spaced pairs of rolls for intermittently feeding a plurality of spaced webs of material into assembled relation and between the folds of the continuously traveling web at spaced points thereon and at right angles thereto, one of each of the last mentioned rolls being a mutilated roll with a portion of its surface cut away and leaving the working surface equal to the length of feed of the material, means for severing a portion from each of said intermittently fed webs, and means for attaching the severed sheets of material together and to the continuously traveling web.

20. In a machine for assembling sheet material, a folding device, a pair of rolls for continuously feeding a web of material through said folding device, a plurality of spaced pairs of rolls for intermittently feeding a plurality of spaced webs of material into assembled relation and between the folds of the continuously traveling web at spaced points thereon and at right angles thereto, one of each of the last mentioned rolls being a mutilated roll with a portion of its surface cut away and leaving the working surface equal to the length of feed of the material, means for severing a portion from each of said intermittently fed webs, and means for attaching the severed sheets of material together and to the continuously traveling web.

21. In a machine for assembling sheet material, means for feeding and folding a web of sheet material, means for feeding a web of material between the folds of the folded material at right angles thereto, means for subsequently severing said web adjacent to the open edges of the folded material, means for feeding an additional web of material towards said folded web to position its end between the open edges thereof and to overlie an end of the first inserted material, means for subsequently severing a portion from said additional inserted material, means for attaching the inserted materials to the folded web adjacent to the open edges thereof, and means for severing the finished units from the folded web.

22. In a machine for making hair waving pads of the type which will assemble together a plurality of webs of materials including a sheet of an

surface equal to the length of feed of the material, and means for attaching the sheets of material together, said last-mentioned means including a sewing machine for continuously stitching said webs of material together while they are moving, said means being provided with a stitching needle moving with the webs of material while forming a loop.

18. In a machine for assembling sheet material, a pair of rolls for continuously feeding a web of material through the machine, a plurality of spaced pairs of rolls intermittently feeding a plurality of spaced webs of material into assembled relation with the continuously traveling web at spaced points thereon and at right angles thereto, one of each of the last mentioned rolls being a mutilated roll with a portion of its surface cut away and leaving the working surface equal to the length of feed of the material, means for severing a portion from each of said intermittently fed webs, and means for attaching the severed sheets of material together and to the continuously traveling web.

19. In a machine for assembling sheet material, a folding device, a pair of rolls for continuously feeding a web of material through said folding device, a plurality of spaced pairs of rolls for intermittently feeding a plurality of spaced webs of material into assembled relation and between the folds of the continuously traveling web at spaced points thereon and at right angles thereto, one of each of the last mentioned rolls being a mutilated roll with a portion of its surface cut away and leaving the working surface equal to the length of feed of the material, means for severing a portion from each of said intermittently fed webs, and means for attaching the severed sheets of material together and to the continuously traveling web.

20. In a machine for assembling sheet material, a folding device, a pair of rolls for continuously feeding a web of material through said folding device, a plurality of spaced pairs of rolls for intermittently feeding a plurality of spaced webs of material into assembled relation and between the folds of the continuously traveling web at spaced points thereon and at right angles thereto, one of each of the last mentioned rolls being a mutilated roll with a portion of its surface cut away and leaving the working surface equal to the length of feed of the material, means for severing a portion from each of said intermittently fed webs, and means for attaching the severed sheets of material together and to the continuously traveling web.

21. In a machine for assembling sheet material, means for feeding and folding a web of sheet material, means for feeding a web of material between the folds of the folded material at right angles thereto, means for subsequently severing said web adjacent to the open edges of the folded material, means for feeding an additional web of material towards said folded web to position its end between the open edges thereof and to overlie an end of the first inserted material, means for subsequently severing a portion from said additional inserted material, means for attaching the inserted materials to the folded web adjacent to the open edges thereof, and means for severing the finished units from the folded web.

22. In a machine for making hair waving pads of the type which will assemble together a plurality of webs of materials including a sheet of an

- absorbent fabric, a sheet of paper and a sheet of a metal foil by sewing them together along one of their respective edges, said machine being provided with holders for continuous rolls of said 5 absorbent fabric material, said paper material and said metal foil material, and runways for receiving said sheet materials when they are taken off said rollers and during assembly, sewing together, separation and imprinting of said hair 10 waving pads; the combination with said machine of means for continuously feeding a web of material through the machine, means for folding said web of material, means for feeding another web of material between the folds of the folded 15 material, means for severing the material so inserted, a sewing machine for sewing said sheet material together while said folded web is being continuously fed, means for pressing the folded web to contact with the inserted material and 20 keep the same in proper position in the fold of the traveling web of material.
23. In a machine for assembling sheet material, a folding device, means for continuously feeding a web of material through said folding device, 25 means for intermittently feeding and inserting a portion of another web of material between the folds of said traveling web, means for severing the material so inserted, and rotatable means for pressing the folded web to contact and hold the 30 inserted material in proper position in the fold of the traveling web of material.
24. In a machine for assembling sheet material, means for continuously feeding a web of material through the machine, means for folding said web of material, means for feeding another web of material between the folds of the folded material, means for severing the material so inserted, rotatable means for pressing the folded web to contact with the inserted material and 40 keep the same in proper position in the fold of the traveling web of material, means spaced from the second mentioned feeding means for feeding an additional web of material towards said folded web to position its end between the open edges 45 thereof and to overlie the severed end of the first inserted material, means for subsequently severing a portion from said additional web, means for attaching the inserted materials to the folded web adjacent to the open edges thereof, and means 50 for severing the finished units from the folded web.
25. In a machine for assembling sheet material, a folding device, means for continuously feeding a web of material through said folding device, 55 means for intermittently feeding and inserting a portion of another web of material between the folds of said traveling web, means for severing the material so inserted, rotatable means for pressing the folded web to contact and hold the inserted 60 material in proper position in the fold of the traveling web of material, said rotatable means consisting of a pair of rolls between which the folded web moves, one of said rolls having a portion of its surface cut away to relieve the pressure 65 on the folded web during the insertion of the said material between the fold.
26. In a machine for assembling sheet material, a folding device, means for continuously feeding a web of material through said folding device, 70 means for intermittently feeding and inserting a portion of another web, means for severing the material so inserted, rotatable means for pressing the folded web to contact and hold the inserted material in proper position in the 75 fold of the traveling web of material, said rotatable means consisting of a pair of rolls between which the folded web moves, one of said rolls having a portion of its surface cut away to relieve the pressure on the folded web during the insertion of the said material between the fold, and 5 means for rotating said rotatable means at a surface speed equal to the rate of speed of the traveling web of material.
27. In a machine for assembling sheet material of the type including means for continuously feeding a web of sheet material through the machine with a continuous feed; the combination therewith of an attaching device consisting of a vertically reciprocating needle bar and needle, means for mounting said needle bar to permit a 10 lateral movement thereof in the upward movement of said bar, and yielding means for retaining said needle bar in its normal vertical position in the downward movement thereof, said mounting means including upper and lower bearings and 15 said yielding means including a resilient member in one of said bearings to permit said lateral movement of the needle with the web of sheet material.
28. In a machine for making hair waving pads 20 composed of a sheet of a non-permeable wrapper and an attached sheet of an absorbent material, the latter to receive liquid and to be placed next to the hair and to be covered and wrapped by said non-permeable wrapper, said 25 non-permeable material being of a material which will be readily torn by a sewing needle if subjected to substantial tension while being sewn, said machine including a holder for a roll of a continuous strip of the wrapper material, a holder 30 for a roll of a continuous strip of the absorbent material, means to assemble said strips together so that they may be sewn, a sewing device including a reciprocating needle, means to pull said wrapper material past the sewing device, 35 means to hold said needle when it descends so that it will penetrate into said strips vertically, means to release said needle after it has penetrated the said strips to permit it to be moved by the wrapper material as said wrapper material is being drawn by the pulling means, and 40 means to restore the needle to its initial position so that it will be inserted vertically downwardly into said strips upon its next downward stroke, after it has been withdrawn upwardly 45 from said strips.
29. In a machine for making hair waving pads 50 composed of a sheet of a non-permeable wrapper and an attached sheet of an absorbent material, the latter to receive liquid and to be placed 55 next to the hair and to be covered and wrapped by said non-permeable wrapper, said non-permeable material being of a material which will be readily torn by a sewing needle if subjected to substantial tension while being sewn, said machine including a holder for a roll of a continuous strip of the wrapper material, a holder for a roll of a continuous strip of the absorbent material, means to assemble said strips together so 60 that they may be sewn, a sewing device including a reciprocating needle, means to pull said wrapper material past the sewing device and said needle being carried by a vertical reciprocating carrier, said sewing device having upper and lower bearings and said lower bearing being capable of lateral movement permitting said needle to be moved by the wrapper material as it is being drawn by the pulling means without tearing thereof during the making of the stitch.
30. In a machine for making hair waving pads 75

- composed of a sheet of a non-permeable wrapper and an attached sheet of an absorbent material, the latter to receive liquid and to be placed next to the hair and to be covered and wrapped by said non-permeable wrapper, said machine including a holder for a roll of a continuous strip of the wrapper material, and a holder for a roll of a continuous strip of the absorbent material, a sewing machine device with a reciprocating needle, drawing and assembly means to draw the strips of the wrapper and absorbent materials off the rolls and to assemble them in superimposed position where they may be sewed together by said sewing machine along one edge thereof, cutter means to cut the strips of said wrapper and absorbent materials to form pieces of the desired length to make up said pad, and synchronizing means to synchronize said drawing and assembling means, and said cutting means, said drawing and assembly means including means to fold the wrapper strip and to insert the absorbent strip therebetween, where it will be sewed into position.
32. A method of automatically making hair waving pads from continuous strips of an absorbent material to receive the treating liquid and be placed next to the hair and of a unpermeable wrapper material to be wrapped around said absorbent material, said method including the steps of advancing the strips to a place of assembly, and cutting and sewing said strips together to form the pad, the wrapper strip being continuously fed and folded and the absorbent strip being intermittently fed transversely to the direction of feeding movement of the wrapper strip, the folded wrapper strip being held open to receive the edge of the feeding absorbent material, the absorbent material then being cut and sewn into position, and the wrapper material being cut after the sewing operation.
33. A method of making hair waving pads of a folded strip of paper enclosing a piece of metal foil and a fabric pad sewn to the edge of the combined paper and foil, comprising the steps of feeding a strip of the paper in one direction toward a place of assembly, and folding it as it is being fed, feeding strips of foil and fabric successively to and transversely toward the folded strip, the foil being fed entirely between the folded strip and the fabric to but only slightly within the folded strip, cutting the foil strip and the fabric strip to permit them to be moved with the folded strip sewing the cut foil and fabric in the folded strip, and then cut the folded strip to form said pads.

CURT J. ROHLAND.
